EXERCISING APPARATUS

Filed Feb. 2, 1929

FIG. 1

FIG. 2

FIG. 3

INVENTOR

F. L. Dyer

UNITED STATES PATENT OFFICE

FRANK L. DYER, OF NEW YORK, N. Y.

EXERCISING APPARATUS

Application filed February 2, 1929. Serial No. 337,123.

My invention relates to improvements in exercising apparatus preferably of the type in which an electric motor operates an endless belt with a vibratory motion and with sufficient power to cause a bodily movement 5 of the user of the apparatus.

To provide an electric motor of sufficient power for the purpose involves the construction of an apparatus of substantial size and 10 weight. If the apparatus is to be concealed after use, it is moved with difficulty and if it is not concealed, it takes up room and is unsightly in appearance. Furthermore, in 15 order to exercise with such an apparatus a considerable pull is imposed upon the endless belt in order that the user may be vibrated bodily; otherwise chafing will result. Therefore, it is generally the practice in using 20 an apparatus of this type to employ a heavy strap therewith which can be firmly secured to some fixed object, such as by being placed under a window sash, the pull upon the apparatus being imposed upon said strap. This 25 is a clumsy and annoying expedient and there is always danger of the strap giving way with a resulting accident.

The essential object of my invention is to provide an exercising apparatus mounted in such a way that it may be quickly and easily 30 concealed and when exposed will be in condition for immediate use. To this end, the invention consists in normally locating the apparatus in a closet or recess normally closed by a door, so that by opening said door the 35 apparatus may be brought into position for operation. The apparatus may be carried upon the door itself or it may be mounted upon an independent support, such as a swinging or hinged bracket extending parallel with the door and preferably connected to the same so that when the door is opened or closed the bracket carrying the exercising apparatus will be correspondingly moved.

The latter modification of the invention 40 will be made the subject of a further application but is comprehended by the claim hereof.

In the present form of the invention, the exercising apparatus is carried upon the door so that the weight of the apparatus is imposed 45 upon the hinges thereof. In order to

prevent the vibrating forces developed by the motor from being imposed upon the hinges, I mount the apparatus so that it may move independently of the door in a horizontal plane and I connect the apparatus to the door jamb 55 or some other fixed structure by means of a strap upon which will be imposed the stresses developed in use.

In order that the invention may be better understood, attention is directed to the accompanying drawing forming part of this specification, and in which

Figure 1 is a horizontal section partly in elevation, illustrating the mounting of the exercising apparatus upon a closet door with 60 the strap secured to the jamb thereof.

Figure 2 is a vertical section of the same.

Figure 3 is an end view showing a portion of the door with the exercising apparatus mounted thereon.

In all the above views corresponding parts are represented by the same numerals.

The exercising apparatus may be of any suitable type. It is here shown as comprising a base 1 on which is mounted an electric motor 2 which causes plungers 3, 3 to reciprocate or vibrate at high speed and to which 75 plungers is secured an endless belt 4, made usually of heavy canvas and which is caused to encircle the waist or other part of the person using the device.

As shown, the base 1 is mounted to slide horizontally with respect to the frame. The latter in the form illustrated, comprises side members 5, 5 with rails 6, 6 upon which the 80 base moves. The side members 5, 5 are secured to the door 7 by screws or in any other suitable way.

I illustrate anti-friction balls 8 on which the base 1 is mounted so that said base will 85 be free to move readily, thus relieving the hinges of the door 7 of all strains due to the operation of the motor 2. Overhanging lugs 9, 9 keep the base 1 in position on the anti-friction balls 8.

A heavy strap 10 is secured to the base 1 and is connected to the door jamb 11 or to any other fixed object so as to absorb stresses due to the operation of the motor.

A lug 12 preferably depends from the base 100

1 and interposed between said lug and a stationary lug 13, is a spring 14 tending to keep the strap 10 always taut. As a matter of convenience, I illustrate shelves 15, 15 arranged between the side members 5 of the supporting frame, which shelves can be used for receiving shoes or other objects of wearing apparel, thus economizing the space in the closet which is taken up by the exercising apparatus and its supporting frame. It will be seen that the spring 14 if used, tends to act also to automatically close the door 7 when the apparatus is to be put out of use.

The operation of the apparatus is obvious, it being only necessary to partially open the door 7, thus bringing the exercising apparatus into view, whereupon it will be employed in the ordinary way.

Having now described my invention, what I claim as new therein and desire to secure by Letters Patent, is as follows:

The combination with a hinged door, of a motor operated exercising apparatus carried by said door and movable in a horizontal plane with respect to the same, a strap connected to the exercising apparatus and a fixed anchorage with which said strap connects for relieving the door of stresses developed in said exercising apparatus.
